CLAIM

The ornamental design for a gift card assembly with removable gift card, sticker and tear strip, as shown and described.

DESCRIPTION

FIG. 1 is a top plan view of a first embodiment of a gift card assembly with removable gift card sticker and tear strip showing my new design;

FIG. 2 is a right side view thereof;

FIG. 3 is a front end view thereof;

FIG. 4 is a bottom plan view thereof;

FIG. 5 is a perspective view thereof;

FIG. 6 is a perspective view of FIG. 1 wherein the gift card assembly with removable gift card, sticker, and tear strip are partially removed from the backing and wherein the pattern illustrates an adhesive surface on the sticker;

FIG. 7 is a top plan view of FIG. 1, without the removable gift card, the sticker and the tear strip shown separately for ease of disclosure;

FIG. 8 is a bottom plan view of the removable gift card, the sticker and tear strip of FIG. 1 without the backing shown separately for ease of disclosure;

FIG. 9 is a top perspective view of the removable gift card with the sticker and tear strip of FIG. 1 shown separately affixed to a bottle for ease of disclosure;

FIG. 10 is a top plan view thereof;

FIG. 11 is a left side view thereof;

FIG. 12 is a right side view thereof;

FIG. 13 is a front end view thereof;

FIG. 14 is a top plan view of a second embodiment of the gift card assembly with removable gift card, sticker and tear strip but without the value box, wherein the right side, front end and bottom plan views of FIG. 14 are identical to right side, front end, and bottom plan views of the first embodiment shown in FIGS. 2, 3, and 4, respectively;

FIG. 15 is a top plan view of a third embodiment of a gift card assembly with removable gift card, sticker and tear strip with the value box of the gift card being located in the upper right corner of the gift card, wherein the right side, front end, and bottom plan views of FIG. 15 are identical to right side, front end and bottom plan views of FIGS. 2, 3, and 4, respectively;

FIG. 16 is a top plan view of a fourth embodiment of the gift card assembly with removable gift card, sticker and tear strip; wherein the value box being located in the lower left corner of the gift card; wherein the right side, front end, and bottom plan views of FIG. 16 are identical to right side, front end, and bottom plan views of FIGS. 2, 3, and 4, respectively;

FIG. 17 is a top plan view of a fifth embodiment of the gift card assembly with removable gift card, sticker and tear strip; wherein the value box being located in the lower right corner of the gift card; wherein the right side, front end, and bottom plan views of FIG. 17 are identical to right side, front end and bottom plan views of FIGS. 2, 3, and 4, respectively;

FIG. 18 is a top plan view of a sixth embodiment of the gift card assembly with removable gift card, sticker and tear strip but without the backing; wherein the right side, front end, and bottom plan views of FIG. 18 are identical to right side, front end and bottom plan views of FIGS. 2, 3, and 4, respectively;

FIG. 19 is a top plan view of a seventh embodiment of the gift card assembly with removable gift card, and tear strip but without the backing sticker; wherein the right side, front end, and bottom plan views of FIG. 19 are identical to right side, front end, and bottom plan views of FIGS. 2, 3, and 4, respectively;

FIG. 20 is a top plan view of a eighth embodiment of the gift card assembly with removable gift card, and tear strip but without the backing and lower portion of sticker; wherein the right side, front end, and bottom plan views of FIG. 20 are identical to right side, front end and bottom plan views of FIGS. 2, 3, and 4, respectively;

FIG. 21 is a top plan view of a ninth embodiment of the gift card assembly with removable gift card, sticker and tear strip located adjacent to the right-hand side of the removable gift card; wherein the right side, front end, and bottom plan views of FIG. 21 are identical to right side, front end and bottom plan views of FIGS. 2, 3, and 4, respectively;

FIG. 22 is a top plan view of a tenth embodiment of the gift card assembly with removable gift card, sticker and tear strip with the tear strip located adjacent to the bottom side of the removable gift card; wherein the right side, front end, and bottom plan views of FIG. 22 are identical to right side, front end, and bottom plan views of FIGS. 2, 3, and 4, respectively; and,

FIG. 23 is a top plan view of a eleventh embodiment of the gift card assembly with removable gift card, sticker and tear strip with the tear strip located adjacent to the top side of the removable gift card; wherein the right side, front end, and bottom plan views of FIG. 23 are identical to right side, front end, and bottom plan views of FIGS. 2, 3, and 4, respectively.

The broken line showing of portions of the gift card assembly with removable gift card stickers is included for the purpose of illustrating environmental structure and forms no part of the claimed design.
